[57] CLAIM

The ornamental design for a carburetor inspection and
repair stand, as shown and described.

DESCRIPTION

FIG. 1 is a top plan view of a carburetor inspection and
repair stand, showing my new design;

FIG. 2 is a side elevational view, the three sides not
shown being identical in appearance thereto; and

FIG. 3 is a bottom plan view thereof.

FIG. 1**FIG. 2**

FIG. 3
